UNITED STATES PATENT OFFICE.

FRANK A. EASTMAN, OF SACO, MAINE, ASSIGNOR OF ONE-HALF TO WILLIAM HARMON, OF SAME PLACE.

SAW-GUARD.

SPECIFICATION forming part of Letters Patent No. 617,239, dated January 3, 1899.

Application filed October 7, 1898. Serial No. 692,879. (No model.)

To all whom it may concern:

Be it known that I, FRANK A. EASTMAN, a citizen of the United States, residing at Saco, in the county of York and State of Maine, have invented new and useful Improvements 5 in Saw-Guards, of which the following is a specification.

This invention relates to improvements in saw-guards for circular saws, and it is carried 10 out as follows, reference being had to the accompanying drawings, wherein—

Figure 1 represents a side elevation of the improved saw-guard as applied to a circular saw. Fig. 2 represents a top plan view of the 15 same. Fig. 3 represents a bottom plan view of the device. Fig. 4 represents a cross-section on the line 4 4 shown in Fig. 1, and Fig. 5 represents a cross-section on the line 5 5 shown in Fig. 1.

Similar letters refer to similar parts wherever they occur on the different parts of the drawings.

In the drawings, A represents the slotted work-supporting table, and B represents the 25 circular saw, secured to the rotary shaft b, as is common in devices of this kind. Below the table A is secured in an adjustable manner the angle-iron C, the horizontal portion of which is provided with a longitudinal slot 30 C', through which passes a screw-bolt D, secured to the table A and provided with a nut d, by means of which said angle-iron may be adjustably secured to the table A and adjusted forward and back relative to the saw 35 in use simply by loosening the nut d and moving the angle-iron accordingly, after which it is secured in the adjusted position simply by tightening the said nut d.

To the vertical portion of the longitudinally- 40 adjustable angle-iron C is secured a vertically-adjustable metal plate or spreader E, which is located in a line with the circular saw B, as shown. The lower portion of said spreader is provided with two or more slots 45 e e e, adapted to receive headed screw-bolts F F F, which are screwed into screw-threaded perforations in the vertical portion of the angle-iron C, and it will thus be seen that said spreader may be vertically adjusted relative 50 to the table A simply by loosening the screws

F F F, after which said spreader may be moved up or down to the desired position for a purpose as will hereinafter be described, and after being so adjusted it may be secured in position simply by tightening the screws 55 F F F.

To the upper portion of the spreader E is pivotally connected an arm or lever G, preferably by means of a screw-bolt H going through said arm or lever and one of a series 60 of perforations E' in the spreader E and having its end preferably screwed into a nut h, arranged in a recess in the opposite portion of said arm G, as shown in Fig. 5.

To the arm or lever G is secured the cap or 65 hood I, which covers and protects the upper portion of the circular saw B, as shown.

By adjusting the spreader E up and down relative to the table A the position of the cap or hood I is adjusted relative to the thickness of the lumber that is being sawed. The forward portion of the arm or lever G is made to rest on the forward upper portion of the spreader E, so as to hold said arm and hood or cap I, attached to it, in a horizontal position, as shown in Fig. 1. 75

By the construction and arrangement as hereinabove shown and described several advantages are obtained, among which may be mentioned that the cap or hood I serves 80 as a proper cover above the saw and prevents articles that may fall upon the table from coming in contact with the saw, thus preventing accidents to the man in charge of the work. By the simple mechanism as described the 85 spreader and cap pivoted to it may be adjusted vertically as well as horizontally relative to the saw, as may be required, and the cap or hood may be adjusted forward and back relative to the spreader by pivoting it 90 to any one of the perforations E' on the said spreader, as may be desired.

In case it is desired to rabbet a plank the spreader and the cap or hood attached to it may easily be removed simply by loosening 95 the bolts F, after which the spreader and its attachment may readily be removed without the removal of said bolts from the angle-iron C or the removal of the latter from the table A.

Having thus fully described the nature, construction, and operation of my invention, I wish to secure by Letters Patent and claim—

In a saw-guard, the combination with the table and a circular saw working therethrough, of an angle-iron having a longitudinal slot and adjustably secured to the under side of the table by means of a bolt passing through said slot and a nut engaging said bolt, a series of bolts carried by said angle-iron, an upright or spreader projecting above said table and having a series of vertically-disposed open-ended slots adapted to receive said bolts,

nuts engaging said bolts and bearing on said upright or spreader whereby to detachably 15 and adjustably secure it to said angle-iron, and a cap or hood pivotally secured to said upright and supported on the upper edge thereof, substantially as described.

In testimony whereof I have hereunto set 20 my hand in presence of two subscribing witnesses.

FRANK A. EASTMAN.
